BOTTLE OPENER

Filed June 26, 1929

UNITED STATES PATENT OFFICE

JOE DE BRACHT, OF EVERETT, PENNSYLVANIA, ASSIGNOR OF ONE-HALF TO GEORGE P. GABLE, OF ALTOONA, PENNSYLVANIA

BOTTLE OPENER

Application filed June 26, 1929. Serial No. 373,847.

This invention relates to a combined bottle cap remover and self pulling cork screw.

A primary object of the invention is to provide a simple and efficient device of this character which may be mounted on a suitable support and which may be used either for removing bottle caps or for withdrawing corks, the device being so constructed that the insertion of the cork screw into the stopper will operate to exert a pulling action on the stopper and automatically withdraw it.

In carrying out these objects, the invention is susceptible of a wide range of modification without departing from the spirit or sacrificing any of the advantages of the claimed invention; there being shown in the drawings for illustrative purposes a preferred and practical form, in which:

Figure 1 represents a front elevation of a device embodying one form of this invention;

Fig. 2 is a longitudinal section taken on the line 2—2 of Fig. 1;

Fig. 3 is a view similar to Fig. 1 showing a slightly different form of cork remover;

Fig. 4 is a longitudinal section taken on the line 4—4 of Fig. 3;

Fig. 5 is a detail perspective view of the bottle engaging member with the cork screw as shown in Fig. 3;

Fig. 6 is a similar view showing still another form of bottle engaging member.

In the embodiment illustrated in Figs. 1 and 2 an obtuse-angled plate 1 constructed of sheet steel or other rigid metal has one member 2 thereof provided with a plurality of screw receiving apertures 3 for fastening the device to a suitable support, the other member 4 of said plate being extended forwardly at an angle to the member 2 and provided with an opening 5 of a size sufficient to receive a bottle mouth and equipped at its lower portion with spaced inwardly extending lugs 6 which constitute top engaging elements as shown in dotted lines in Fig. 2.

The support engaging plate 2 is provided at its upper end with laterally and forwardly extending apertured ears 7 which are struck out of the plate 2 intermediate the width

thereof and bent forwardly in parallel relation with a spacing portion 8 between them. These ears are designed to receive between them the terminal eye 12 of a cork screw shank 11, 10 designating the cork screw as a whole. This eye 12 is pivotally mounted between the ears 7 on a suitable pintle 9 so that the cork screw may be swung inwardly and outwardly at the will of the user.

To lock the cork screw 10 in inoperative position the base plate 2 is provided with an undercut lug 13 which is slightly off center relatively to the longitudinal axis of the cork screw and located in position to receive the spur or point of the cork screw when the cork screw is set slightly to one side permitting the point to pass under the lug.

At opposite sides of the plate 2 in alignment with the lugs or ears 7 are two apertured ears 14 struck out of plate 2 and bent forwardly to receive the terminals 16 of a bottle mouth receiving member 15 whereby the latter is pivotally mounted. This member 15 is made U-shaped in form with double laterally spaced parallel legs 18 and 19, the inner legs 18 being shorter than the outer legs 19 and joined at their outer ends by a cross bar 20 with a forward longitudinal projection 21 at the connection with the cross bar with the legs 19. This cross bar 20 forms a shoulder which is designed to be engaged by the mouth of the bottle from which the cork is to be removed the projections 21 holding such bottle mouth against lateral movement. The shank or stem 11 of the cork screw 10 passes through the main cross bar or body portion 22 of the member 15 as shown clearly in Fig. 1 so that when this member 15 is swung on its pivot the cork screw will move with it and vice versa.

When it is desired to remove a cork from a bottle the member 15 is swung out laterally in the dotted line position shown in Fig. 2 and the bottle is placed with the edge of its mouth abutting the shoulders 20 after the cork screw has been engaged with the stopper by turning the bottle against the cork screw. After the bottle reaches the position with its mouth engaging the shoulders 20 the continued turning of the bottle will

obviously cause the cork screw to continue to enter the stopper and exert a pulling action on the stopper, automatically removing it.

When not in use the member 15 carrying 5 with it the cork screw 10 is swung down into the full line position shown in Figs. 1 and 2 and by inserting the point in the housing 13 as above described the cork screw and the member 15 will be held in this position until 10 it is again desired to use it.

To remove a bottle cap the mouth of the bottle is inserted through the opening 5 as shown in dotted lines in Fig. 2 and the edge of the cap engaged with the prongs 6 and by 15 an upward pull on the bottle the cap will be removed.

In the form shown in Figs. 3, 4 and 5 the supporting plate 1 is the same as that shown in Figs. 1 and 2 being composed of two leaves 20 2 and 4 except that leaf 2 has no outstruck apertured ears at the side edges thereof such ears being provided and arranged intermediate the width of the plate 2 to form bearings for a pintle 9^a which extends also through the 25 eye 12 of the cork screw. Mounted on this pintle 9^a is also a cork removing element 15^a.

This member 15^a comprises two L-shaped arms 23 and 24 provided at their inner ends on the short portions thereof with parallel 30 longitudinally extending apertured fingers 25 and 26 which are arranged on the pintle 9^a outside the apertured ears 7 between which the cork screw is mounted. These L-shaped arms 23 and 24 are connected by a cross bar 35 27 and the fingers 25 and 26 are notched on their inner corners as shown at 28, said notches being designed to engage the lower end of the opening formed by the striking out of the lugs 7. The arms 23 and 24 are spaced apart a distance sufficient to receive the cork 40 or stopper from the bottle and at the ends of these arms are formed outwardly offset shoulders 20^a against which the mouth of the bottle is designed to abut, forwardly extending fingers 21^a being provided on these shoulders to restrict the lateral movement of the bottles.

In the use of this form of cork remover the member 15^a is swung upwardly at right angles to plate 2 as shown in Fig. 4 with the notches 28 engaging the plate and is then ready for use.

In the form shown in Fig. 6 the cork remover 15^b is shown constructed of a single strip of strap metal doubled upon itself and shaped into a U-shaped member with the terminals of said strap extended laterally and rearwardly and spaced apart as shown at 7^b and between which the eye of the cork screw is designed to be mounted, said ends being 55 apertured for the passage therethrough of the cork screw attaching pintle, said pintle also operating to attach the member 15^b to the supporting plate in connection with which it is to be used. The cross bar 22^b has an aperture 29 for the insertion of the stem of

the cork screw while at the outer ends of the arms 23^b and 24^b are formed laterally offset bottle mouth engaging shoulders 20^b at the outer sides of which extend forwardly stops 21^b to limit the lateral movement of the bottle mouth.

This member 15^b may be substituted for the member 15^a and is designed to perform the same function.

From the above description it will be obvious that this cork puller requires no force 75 to be exerted thereon and simply by turning the bottle with the cork screw engaged with the stopper the pressure of the bottle mouth against the stops on the members which carry the cork screw will cause the stopper to be 80 withdrawn.

Without further description it is thought that the features and advantages of the invention will be readily apparent to those skilled 85 in the art, and it will, of course, be understood that changes in the form, proportion and minor details of construction may be 90 resorted to, without departing from the spirit of the invention or its scope as claimed.

I claim:

1. A cork remover having a base to be secured to a supporting surface, a cork screw and a bottle mouth engaging member mounted to swing on said base, said bottle engaging member being U-shaped in form with an aperture in its cross bar for the passage of the cork screw stem, the outer end of said member having offset shoulders for engagement by the mouth of the bottle, the cork being designed to pass between the arms of said member.

2. A cork remover comprising a supporting structure, a bottle mouth engaging member pivotally mounted on said structure and having a socket to receive a cork, a cork screw carried by said member and held rigidly in relation thereto and adapted to move with the member, said member being U-shaped and having offset shoulders at its outer ends against which the edge of the bottle mouth is designed to abut to properly position the cork in relation to the cork screw.

JOE DE BRACHT.
